J. J. Murray
ATTORNEY

UNITED STATES PATENT OFFICE

GEORGE C. HENDERSON, OF DETROIT, MICHIGAN

MONORAIL TRACK

Application filed February 10, 1930. Serial No. 427,207.

This invention relates to railway tracks, and particularly to mono-rail tracks.

An object of the invention is to provide a track comprising a pair of parallel rails, so vertically spaced that their engagement by wheels mounting and suspending a car will largely restrain the car from side sway.

Another object is to so insulate said rails from each other that they may form opposite sides of an electric circuit, energizing the drive motor of said car.

A further object is to form such a pair of spaced rails of sheet metal strips rolled to a **U** cross section, and to space them apart by plates of insulating material having opposite margins fitting into and rigidly secured in the openings of said rails.

Still another object is to provide improved means for quickly establishing both an electrical and mechanical connection between the ends of adjacent sections of a mono-rail track.

These and various other objects the invention attains by the construction hereinafter described and illustrated in the accompanying drawings, wherein:

Fig. 1 is a view in end elevation of the improved track, as particularly adapted for toy railway use, showing one of the track supports and indicating a car arranged to travel on said track.

Fig. 2 is a view of a length of the track in side elevation and partial section.

Fig. 3 is an enlarged end view of a section of the track.

Fig. 4 is a cross sectional view of the same, taken upon the line 4—4 of Fig. 2.

Fig. 5 is a perspective view of one of the insulating plates and its attached metal side plates.

In these views, the reference character 1 designates a pair of rails formed from sheet metal strips rolled or otherwise fashioned to a **U** cross section. Said rails are spaced rigidly apart in a parallel relation by a plurality of insulating plates 2, 3, and 4, whereof any suitable number may be employed. In a track of toy proportions, these plates may be stamped from sheet fibre or the like. The rails 1 straddle respectively the upper and

lower margins of said plates, and are riveted or otherwise rigidly secured thereto, as indicated at 5. The plates 2 and 4 are spaced from the bends of the rails 1, and a pair of connectors 6, formed of stiff wire are permanently engaged between each plate 2 and said bends, projecting beyond the adjacent ends of said rails to snugly fit between the plate 4 of an adjoining track section and the rail bends thereof. To hold the connectors 6 rigidly in place, their inner ends are bent toward each other, as indicated at 7, and engaged in notches 8 oppositely formed in plate 2.

While the described track may be supported in any suitable manner, it is preferred to mount the ends of the track sections upon posts 9 having horizontally projecting top portions, to which the track is attached by screws 10. A car operating on said track is indicated at 11, and 12 and 13 designate wheels engaging respectively the upper and lower rails of said track and journaled upon a standard 14 rigidly surmounting said car. Preferably a pair of metal plates 15 are riveted or otherwise rigidly secured to the plates 2 and 4 at each side thereof, providing bearing faces for engagement by the posts 9 and screws 10.

The parts of the described track are inexpensive and readily assembled, and the construction lends itself to the use of machinery in effecting assembly.

While the construction as illustrated is particularly designed for toy purposes, the structural principles involved are more or less applicable to full size mono-rail systems. The vertically spaced relation of the rails established by the invention is particularly desirable in providing for use of upper and lower grooved wheels supporting a suspended car, and restraining the car from side sway, such restraint being particularly necessary when the car is making a turn.

While it is apparent that the illustrated embodiment of my invention herein disclosed is well calculated to adequately fulfill the objects and advantages primarily stated, it is to be understood that the invention is susceptible to variation, modification and

change within the spirit and scope of the subjoined claims.

What I claim is:

1. A mono-rail track comprising a pair of spaced upper and lower rails, and a plate of insulation rigidly connecting said rails.
2. A mono-rail track comprising a pair of spaced upper and lower rails of U section, an insulating plate having its upper and lower portions straddled by said rails, and means rigidly securing said rails to said plate.
3. A mono-rail track comprising a pair of spaced upper and lower rails of U section, an insulating plate having its upper and lower portions straddled by said rails, and a pair of connectors secured between said plate and the U bends of said rails, and projecting beyond an end of said track.
4. A mono-rail track comprising a pair of spaced upper and lower rails of U section, an insulating plate having its upper and lower portions straddled by said rails, and having notches in said portions, and a pair of connectors snugly engaged between said plate and the U bends of said connectors and having ends bent toward each other and engaged in said notches to hold said connectors projecting beyond an end of the track.
5. A mono-rail track comprising a pair of spaced upper and lower rails of U section, insulating plates rigidly connecting the end portions of said rails, and marginally straddled by said rails, the upper and lower edges of each plate being correspondingly spaced from the U bends of said rails, and a pair of connectors snugly retained between one of said plates and said U bends, the spaces between the other of said plates and said U bends forming sockets to engage similar connectors on another such section of track.
6. A mono-rail track comprising a pair of electrically conductive rails of U section, and means straddled by each of said rails rigidly connecting said rails and insulating them from each other.
7. In a mono-rail track, a conductive rail of U section, an insulating member straddled by said rail and spaced from the bend of said rail to form a pocket, a connector inserted in said pocket and projecting beyond an end of the rail, and means securing said insulating member to said rail.
8. The construction set forth in claim 7, the insulating member having a notch opposed to the bend of said rail, and said connector being bent to engage in said notch.
9. A mono-rail track section, comprising a pair of spaced rails, forming opposite sides of an electric circuit, means rigidly connecting said rails and insulating them from each other, and a pair of connectors electrically and mechanically connected to said rails at one end of said section and projecting beyond said end, the rails being formed at the other end of said section with a pair of sock-

ets aligned longitudinally of the section with said connectors, and proportioned to frictionally retain the connectors of an adjoining section.

10. A mono-rail track comprising a pair of spaced conductive rail members, means rigidly connecting said rail members, insulating them from each other, and a pair of connectors secured by the last named means in individual electrical contact with said rail members, and projecting beyond corresponding ends of said rail members.

In testimony whereof I sign this specification.

GEORGE C. HENDERSON.
